STUDIO COUCH

Ira M. Pink and Victor Bergstrom, Chicago, Ill.,
assignors to Superior Felt & Bedding Co., Chi-
cago, Ill., a corporation of Delaware

Application July 22, 1938, Serial No. 220,632

9 Claims. (Cl. 5—18)

The present invention relates to improvements in studio couches, and has particularly reference to a new and improved studio couch having two relatively slidable sections adapted to be positioned in nested or superimposed relation for use as a seat or lounge, and to be moved into relatively projected position to provide a double sleeping surface.

One of the objects of the invention is to provide a couch of the foregoing character having a novel actuating mechanism interconnecting the couch sections, and operable with a positive mechanical action to effect movement of the couch sections either into relatively projected position or relatively retracted position.

A further object is to provide a twin section studio couch of the foregoing character in which one of the sections is provided with a swinging back connected to the actuating mechanism, and adapted in its swinging movements to serve as an actuating lever movable synchronously with the relative sliding movement of the sections.

Another object is to provide a new and improved actuating mechanism for relatively sliding the two sections of a twin section studio couch into and out of nested relation which is operable to lock the sections selectively in either of the two extreme positions of relative adjustment.

A further object is to provide a novel actuating mechanism of the foregoing character which can be operatively disconnected from one of the sections only when the sections are in extended position so that the sections may be separated for independent use.

A further object is to provide a new and improved actuating mechanism which includes equalizing means for insuring uniform movement of the opposite ends of the movable couch section.

A general object of the invention is to provide a novel twin section studio couch having an actuating mechanism interconnecting the sections which is simple and inexpensive in construction, which is easy to operate, and which is substantially concealed from view when the sections are in assembled relation.

Other objects and advantages will become apparent as the description proceeds.

In the accompanying drawings, Figure 1 is a fragmentary transverse vertical sectional view, taken substantially along line 1—1 of Fig. 4, of a couch embodying the features of my invention.

Fig. 2 is a view similar to Fig. 1, taken substantially along line 2—2 of Fig. 3, but illustrat-

ing the couch sections in relatively projected position.

Fig. 3 is a fragmentary plan view of the couch with the sections in relatively projected position.

Fig. 4 is a fragmentary longitudinal vertical sectional view of the couch taken substantially along line 4—4 of Fig. 1.

Fig. 5 is a fragmentary view similar to Fig. 1, but illustrating a modified form of the invention.

Fig. 6 is a fragmentary view similar to Fig. 1, but illustrating another modified form of the invention.

Fig. 7 is a view similar to Fig. 6, but illustrating the couch sections in relatively projected position.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the spirit and scope of the invention as expressed in the appended claims.

Referring more particularly to the drawings, the couch illustrated in Figs. 1 to 4, and constituting one embodiment of the invention, comprises two relatively slidable couch sections 1 and 2 adapted to be nested or telescoped in vertically superimposed relation as illustrated in Figs. 1 and 4, or to be adjusted into separated or relatively projected position as illustrated in Figs. 2 and 3. One of the sections, for example, the bottom or inner section 1, may be stationary and the other section, for example, the top or outer section 2, may be slidable. In the present instance, the stationary section 1 is provided with a rectangular horizontal reenforced frame 3 having vertical corner legs 4 adapted to rest in fixed position on the floor, and having a longitudinal front channel member 5. A suitable spring structure 6 is mounted in the frame 3, and is adapted to receive a sleeping pad or cushion 7 when the stationary section 1 is uncovered.

The top or movable couch section 2 comprises a border frame 8 open at the rear to receive the stationary section 1, and more particularly comprising a longitudinal front channel member 9 and end channel members 10. A rear longitudinal angle bar 11 spans and is secured to the tops of the rear ends of the frame members 10.

Each of the frame members 9 and 10 has upper and lower flanges 12 and 13 extending inwardly in vertically spaced relation.

The section 2 is supported by four corner legs 14 which are secured to the lower flanges 13 of the end members 10, and which are provided with casters 15 adapted to roll on the floor. Aprons 16, also secured to the lower flanges 13 of the frame, serve to conceal the legs 14 substantially from view.

Mounted on the top of the frame 9, 10 is a box spring structure 17 adapted to provide a seating surface or a sleeping surface. A cushion 1 may be interchangeably positioned on the spring structure 17 when the couch sections 1 and 2 are in relatively retracted position, or on the spring structure 6 when the sections are in relatively extended position. The spring structure 17 may be covered with upholstery material 18.

Secured to the outside of the frame end members 10 and rising therefrom are two upright arm rests 19. Each of these rests consists of an end frame substantially in the form of an inverted U, with the upper rear corner rounded as indicated at 20, and with the leg portions connected by a horizontal crossbar 21. The couch section 2 is provided with a longitudinal back rest 22 having generally L-shaped end members 23 pivotally connected adjacent their free ends, as at 24, respectively to the crossbars 21. Attached to the vertical portions of the members 23 are two curved lugs or yieldable pads 25 adapted to seat respectively on the rear corners 20 of the arm rests 19 to support the back rest 22 in rear position as shown in Fig. 1, when the sections 1 and 2 are in relatively retracted position. The back rest 22 is pivotal from its rear position into a forward position substantially against the front member 9 of the section 2 as shown in Fig. 2.

The two couch sections 1 and 2 are positively interconnected by a mechanical actuating mechanism operable by the back rest 22 in the capacity of a lever to move the section 2 in synchronism with the back rest into projected or retracted position relative to the section 1.

The actuating mechanism, at each end of the couch, comprises a lever 26 of the third order, one end of which is pivotally connected at 27 to an inwardly extending bracket arm or lug 28 rigidly secured to the upper flange 12 of the adjacent frame end member 10, and the other end of which is pivotally connected by a pin 29 to the front channel member 5 of the couch section 1. The pin 29 is rigidly fixed to the lever 26, and extends downwardly through an elongated slot 30 in the upper forwardly projecting flange of an angle bracket 31 secured to the front of the frame member 5. The lower end of the pin 29 is flattened to provide a flared key 32 rotatable, as an incident to the swinging of the lever 26, into interlocking relation to the slot 30. Except when the couch section 2 is substantially in fully projected position, the pin 29 is not readily accessible, and the locking key 32 is not in parallel alignment with the slot 30, and hence prevents separation of the lever 26 from the bracket 31. The slot 30 permits relative shifting of the pin 29 to accommodate the arcuate movement of the latter as the lever 26 is swung from either extreme position to the other.

The lever 26 is pivotally connected intermediate its ends to a link 33 in turn pivotally connected to a slide bar 34 mounted on the adjacent

frame member 10 for longitudinal movement transversely of the couch section 2. To provide means for supporting and guiding the bar 34, two depending brackets 35 are fixed to the upper flange 12 of the frame member 10 at opposite sides of the bracket arm 28. Headed pins 36 extend through two longitudinal slots 37 in the bar 34, and confine the latter slidably against the brackets 35.

10 The rear end of the bar 34 is pivotally connected to one end of a link 38 which is bent to extend first upwardly, then forwardly and finally upwardly and forwardly at an angle, and the forward end of which is pivotally connected by a pin 39 to the end of a lever arm 40 pivoted to the crossbar 21 at 24 and constituting an extension of the horizontal portion of the adjacent end member 23 of the back rest 22.

When the back rest 22 is in its rear position and also when it is in its forward position, the pin 39 is located substantially in the same horizontal plane as the pivot 24, and consequently the couch sections 1 and 2, when either in relatively projected position or relatively retracted position, are locked against relative movement except through swinging actuation of the back rest 22 acting as a lever of the first order.

15 The two levers 26 at the opposite ends of the couch are interconnected by equalizing means to insure straight line movement of the couch section 2. This means consists of two crossbars 41 secured respectively to the levers 26 adjacent the pivots 27, and cross cables 42 connecting the ends of each bar respectively to the reverse ends 25 of the other bar.

20 In operation, when it is desired to project the couch section 2 from the couch section 1, the back rest 22 is swung forwardly. The end members 23 of the back rest 22 operate as levers of the first order, and act through the arms 40 and the links 38 to shift the bars 34 rearwardly on the frame members 10. As a result, the bars 34 act through the links 33, as represented in Fig. 3, to swing the levers 26 of the third order from their forward position (illustrated in dotted outline) to their rear position (illustrated in full outline), the slots 30 accommodating the arcuate movement of the pins 29. Since the pivots defined by the pins 29 are fixed to the couch section 1 against movement laterally of the couch, the section 2 is forced or projected forwardly off of the section 1 in harmonic synchronization with the progressive forward swinging movement of the back rest 22. Upon returning the back rest 22 into its rear position, the action is reversed to move the couch section 2 into retracted position over the section 1.

25 Fig. 5 illustrates a modified form of the invention in which the back rest is permitted a limited swinging movement before actuation of the upper or top couch section. In all other respects, the two forms are substantially alike in construction, and hence the parts of the second form are identified by the same reference numerals, with the addition of the letter *a*, as the corresponding parts of the first form, and only the structural and functional differences will be described.

30 In Figs. 1 to 4, the pivot pin 39 extends through a closely fitting hole in the forward end of the link 38. In Fig. 5, the pin 39a extends through a longitudinal slot 43 in the link 38a of such length that the back rest 22a will swing forwardly through a small angle, for example, into the dotted position indicated in Fig. 5, before

the actuating mechanism will begin to project the couch section 2^a into forward position, and likewise that the back rest will swing rearwardly through a small angle before the actuating mechanism will begin to return the couch section 2^a into retracted position.

Apart from the slight initial swinging movement of the back rest 22^a in projecting the upper section 2^a forwardly or in retracting the section 2^a from projected position, the couch of Fig. 5 operates in the same manner as the couch of Figs. 1 to 4. Movement of the upper section 2^a, throughout its entire range, is attended and caused by swinging movement of the lever back 22^a in timed relation.

Figs. 6 and 7 illustrate another modified form of the invention which is closely similar to the form of Figs. 1 to 4, and of which the parts corresponding to parts of the first form are identified by the same reference numerals plus the letter *b*. In this form, the mechanical connection between the slide bars 34^b and the frame 3^b of the section 1^b is exactly the same as that between the bars 34 and frame 3 in Figs. 1 to 4, but the connection between the bars 34^b and the end members 23^b of the back rest 22^b is different. More particularly, the rear end of each bar 34^b is connected through a generally horizontal link 44 to the lower end of a generally vertical lever 45 pivoted intermediate its ends at 46 on a lug 47 secured to the rear leg of the adjacent arm rest 19^b. A generally horizontal link 48 is connected at the rear end to the upper end of the lever 45, and at the front end by a pin 49 to the associated end member 23^b of the back rest 22^b. In this instance, the pin 49 is spaced from the end of the member 23^b which acts as a crank about the center 24^b to oscillate the lever 45 in synchronism with the swinging movements of the rest 22^b.

We claim as our invention:

1. A twin studio couch comprising, in combination, a normally stationary couch section, a normally movable couch section mounted for rectilinear movement into and out of position over said stationary section, a back rest having end members pivotally mounted on opposite ends of said movable section for swinging movement from a back position into a forward position, an actuating mechanism at one end of said movable section comprising a lever pivoted to said movable section, a bracket fixed on said stationary section and having a longitudinal slot, a pin on said lever projecting slidably through said slot and formed with a key preventing separation from said bracket except when said sections are in relatively extended position, and means interconnecting said lever with said back rest to swing said lever in timed relation to the swinging movement of said back rest, a duplicate actuating mechanism at the other end of said movable couch section, crossbars secured to said levers of said actuating mechanisms, and cross cables connecting the opposite ends of said bars to equalize the movement of said levers.

2. A twin studio couch comprising, in combination, a normally stationary couch section, a normally movable couch section mounted for rectilinear movement into and out of position over said stationary section, a back rest having end members pivotally mounted on opposite ends of said movable section for swinging movement from a back position into a forward position, an actuating mechanism at one end of said movable section comprising a lever pivoted to said movable

section, a bracket fixed on said stationary section and having a longitudinal slot, a pin on said lever projecting slidably through said slot and formed with a key preventing separation from said bracket except when said sections are in relatively extended position, and means interconnecting said lever with said back rest to swing said lever in timed relation to the swinging movement of said back rest, a duplicate actuating mechanism at the other end of said movable couch section, and means for coordinating the operation of said actuating mechanisms so as to equalize the movements of the opposite ends of said movable section.

15 3. A twin studio couch comprising, in combination, a normally stationary couch section, a normally movable couch section mounted for rectilinear movement into and out of position telescoping with said stationary section, a back rest having end members pivotally mounted on opposite ends of said movable section for swinging movement from a back position into a forward position, an actuating mechanism at one end of said movable section comprising a horizontal inwardly extending lever under said movable section pivoted at one end to said movable section for swinging movement generally transversely of said sections and pivoted at the other end through a longitudinal sliding connection to said stationary section, and means interconnecting said lever with said back rest to swing said lever in timed relation to the swinging movement of said back rest whereby to effect relative transverse movement of said sections, a duplicate actuating mechanism at the other end of said movable couch section, and means for coordinating the operation of said actuating mechanisms so as to equalize the movements of the opposite ends of said movable section.

40 4. A twin studio couch comprising, in combination, a normally stationary bottom couch section having a longitudinal front frame member, a top couch section slidably movable into and out of position over said stationary section and having a frame with opposite end frame members and open at the rear to receive said stationary section, arm rests secured to the ends of said last mentioned frame, a back rest having end members pivoted respectively to said arm rests and being movable rearwardly into stop engagement with said arm rests to define a normal back position and movable forwardly into a front position clear of the top of said movable section, two actuating mechanisms respectively at opposite ends of said movable section, each actuating mechanism comprising an inwardly extending lever connected at the outer end to the adjacent end frame member of said movable section and at the other end for pivotal and relative longitudinal sliding movement to said front frame member, a slide bar mounted on the adjacent end frame member for movement transversely of said section, a pivotal link interconnecting said slide bar and said lever, a vertical lever pivoted on the rear of said movable section and pivotally connected at the lower end through a link to the rear end of said bar, and a link pivotally connecting the upper end of said vertical lever to the adjacent end member of said back rest eccentrically of the back rest pivot, and means for equalizing the swinging movement of said actuating levers.

75 5. A twin studio couch comprising, in combination, a normally stationary bottom couch section having a longitudinal front frame member, a top

couch section slidably movable into and out of position over said stationary section and having a frame with opposite end frame members and open at the rear to receive said stationary section, a back rest having end members pivoted respectively to said end frame members and being movable rearwardly into a normal back position and movable forwardly into a front position clear of the top of said movable section, two actuating mechanisms respectively at opposite ends of said movable section, each actuating mechanism comprising an inwardly extending lever connected at the outer end to the adjacent end frame member of said movable section and at the other end for pivotal and relative longitudinal sliding movement to said stationary section, a slide bar mounted on said adjacent end frame member and connected to said lever for synchronous movement transversely of said movable section, and a pivotal link interconnecting said slide bar and the adjacent end member of said back rest for movement in timed relation.

6. A twin studio couch comprising, in combination, a normally stationary bottom couch section having a longitudinal front frame member, a top couch section slidably movable into and out of position over said stationary section and having a frame with opposite end frame members and open at the rear to receive said stationary section, arm rests secured to the ends of said last mentioned frame, a back rest having end members pivoted respectively to said arm rests and being movable rearwardly into stop engagement with said arm rests to define a normal back position and movable forwardly into a front position clear of the top of said movable section, two levers of the third order pivoted to said end frame members and extending inwardly therefrom, pin and slot connections between said levers and said front member, two horizontal bars slidably confined for reciprocation transversely of said sections on said end frame members, two links pivotally connecting said levers to said bars, two links pivotally connected to the rear ends of said bars and pivotally connected to said end members eccentrically of the connections of said end members with said arm rests, and means equalizing the movements of said levers, whereby said back rest is operable in its swinging movement to effect movement of said movable section in timed relation.

7. A twin studio couch comprising, in combination, a normally stationary couch section, a movable couch section mounted for rectilinear movement into and out of telescoping relation to said stationary section, a back rest mounted for swinging movement on said movable section either into a normal back position or into a forward position clear of the top of said movable section, said back rest including a back rest member extending longitudinally from one end to the other end of said couch, and mechanical means positively interconnecting said back rest and said

stationary section and operable to slidably project said movable section forwardly from said stationary section upon swinging movement of said back rest into forward position and to slidably retract said movable section rearwardly upon swinging movement of said back rest into back position, said connection including a lost motion permitting a free initial movement of said back rest in either direction and thereafter effecting movement of said movable section in timed relation to the swinging movement of said back rest, whereby the forward movement of said movable section is delayed to avoid inconvenience to the operator in the forward swinging movement of said back rest member.

8. A twin studio couch comprising, in combination, a normally stationary couch section, a couch section slidably movable into and out of position telescoping with said stationary section and having a frame with opposite end frame members, a back rest having end members with pivotal connections to said end frame members and being movable rearwardly into a normal back position and movable forwardly into a front position clear of the top of said movable section, a lever of the third order pivoted to one of said end frame members and extending inwardly therefrom, pin and slot connection between the other end of said lever and said stationary section, a horizontal bar slidably confined for reciprocation transversely of said sections on said one end frame member, a link pivotally connecting said lever and said bar, and a link connecting said bar and the adjacent end member of said back rest, said last mentioned link having a pivotal pin and slot connection with said one end member of said back rest to permit independent swinging of said back rest over a predetermined range and then timed movement of said back rest and said movable section.

9. A twin studio couch comprising, in combination, a normally stationary couch section, a normally movable couch section mounted for rectilinear movement into and out of position over said stationary section, a back rest having end members pivotally mounted on opposite ends of said movable section for swinging movement from a back position into a forward position, an actuating mechanism at one end of said movable section comprising a lever pivoted to said movable section, a bracket fixed on said stationary section and having a longitudinal slot, a pin on said lever projecting slidably through said slot, and means interconnecting said lever with said back rest to swing said lever in timed relation to the swinging movement of said back rest, a duplicate actuating mechanism at the other end of said movable couch section, cross bars secured to said levers of said actuating mechanisms, and cross cables connecting the opposite ends of said bars to equalize the movement of said levers.
